(57) **CLAIM**

We claim the ornamental design for a portable hand washstand, as shown and described.

DESCRIPTION

FIG. 1 is a top, front, right perspective view of a portable hand washstand, showing our new design;

FIG. 2 is a top, rear, left perspective view thereof;

FIG. 3 is a front elevational view thereof;

FIG. 4 is a rear elevational view thereof;

FIG. 5 is left side elevational view thereof;

FIG. 6 is a right side elevational view thereof;

FIG. 7 is a top plan view thereof;

FIG. 8 is a bottom plan view thereof;

FIG. 9 is a cross-sectional view thereof taken along line 9-9 in FIG. 7, with the internal mechanisms omitted; and,

FIG. 10 is a cross-sectional view thereof taken along line 10-10 in FIG. 7, with the internal mechanisms omitted.

The broken lines in the drawings depict portions of the portable hand washstand that form no part of the claimed design.

1 Claim, 5 Drawing Sheets
